Primary Examiner — Steven J Czyz*Assistant Examiner* — Matthew O Williams(74) *Attorney, Agent, or Firm* — Ricky Lam(57) **CLAIM**

The ornamental design for a weight bracelet, as shown and described.

DESCRIPTION

FIG. 1 is a top perspective view of a weight bracelet, showing my new design;

FIG. 2 is a bottom perspective view thereof;

FIG. 3 is a front view thereof;

FIG. 4 is a rear view thereof;

FIG. 5 is a left side thereof;

FIG. 6 is a right side view thereof;

FIG. 7 is a top view thereof;

FIG. 8 is a bottom view thereof;

FIG. 9 is a perspective view of a single weight of the weight bracelet, show separately for ease of disclosure;

FIG. 10 is a perspective view of the weight bracelet, shown in a state of use;

FIG. 11 is a perspective view of the weight bracelet, shown in use and with a different style of wrist band in broken lines; and,

FIG. 12 is another perspective view thereof, but shown in an open state of use.

The broken lines in the drawings illustrate the portions of the weight bracelet, which form no part of the claimed design.
